UNITED STATES PATENT OFFICE.

FOLKE FREDRICK NORDEN, OF NEW YORK, N.Y.

ABDOMINAL SUPPORTER.

Application filed April 22, 1921, Serial No. 463,497. Renewed July 12, 1924.

To all whom it may concern:

Be it known that I, FOLKE FREDRICK NORDEN, a citizen of the United States, residing at New York, in the county of New York and State of New York, have invented certain new and useful Improvements in Abdominal Supporters; and I do hereby declare the following to be a full, clear, and exact description of the invention, such as will enable others skilled in the art to which it appertains to make and use the same.

This invention relates to new and useful improvements in abdominal supporters and more particularly to that type which are worn to replace the well known corset and the main object of this invention is the provision of a device of this character constructed in such a manner as to provide for suitable expansion and contraction of the device so that it may be comfortably worn by different sized figures.

Another object of the invention is the provision of a device of this character constructed of two or more substantially C-shaped resilient members suitably connected and provided with the usual whale-bone connections used in the construction of corsets at the present time and provide suitable covering for the different members outlining the construction of the device so that the same can be worn with comfort.

A still further object of the invention is the provision of a device of the above character wherein the bands used in the construction of the same can be quickly and readily adjusted so as to accommodate the same to figures of various sizes and also to eliminate the usual fastening members used on corsets at the present time which consists of the lacing and the well known form of hooks.

A still further object of the invention is to provide in combination with a supporter of the above character, an adjustable bust support attached to the body of the supporter so that the same can be readily adjusted to the accommodation of the person wearing the support.

With the above and other objects in view the invention consists in the novel features of construction, combination and arrangement of parts hereinafter more fully set forth, pointed out in the claims and shown in the accompanying drawings in which:

Figure 1 is a front perspective of a supporter constructed in accordance with my invention illustrating the application of the

same, parts thereof being broken away and shown in section;

Fig. 2 is a rear perspective, parts thereof being broken away and shown in section;

Fig. 3 is a detail perspective view of the frame of my improved supporter;

Fig. 4 is a detail perspective view showing the application of the adjusting plate;

Fig. 5 is a detail perspective view of one of the spring members taken at the point of attachment of the adjusting plate, and

Fig. 6 is a detail perspective view showing the adjustable connection of the bust support with the main support.

In the construction of my invention, I employ an upper band 1, a lower band 2 and an intermediate diagonal band 3. The upper band 1, when applied to the body of the wearer is arranged at a point just above the hip lines, while the lower band 2 is arranged at a point near the widest portion of the hip, the intermediate band 3 is connected at its central portion to the central portion of the upper band 1 as shown at 4 and is curved diagonally down around the hips between the upper and lower band and the ends of this intermediate band are secured as at 5 to the ends of the lower band 2.

While I have shown and described the intermediate band 3 as connected to the upper band 1 by riveting or other similar fastening means, I wish it to be understood that this band 3 may, if found suitable, be formed integral with the upper band 1 at their intermediate portions so as to provide a smooth and unbroken surface at this point. It will be noted that one of the ends of the upper band 1 is bifurcated as shown at 6, while the other end thereof is movably disposed within this bifurcated portion so that the front portion of the support will be closed at this point.

The three bands comprising the body portion of the support are constructed from suitable resilient material such as spring steel, and suitably connected by transverse members 7 preferably of the usual whale-bone type which are used in the construction of corsets at the present time and the entire frame work is covered with any suitable and desirable material.

From this, it will be apparent that I have provided a suitable supporter which produces an improved effect over the well known form of corset used at the present

time, a. at the same time is comfortable in its fitting and provides a neat appearance in its finished state.

In order to provide for the adjustment of the resilient bands 1, 2, and 3, each of the bands, if found necessary, may be provided with suitable adjusting members which in the present instance are shown as plates 8 having a plurality of eyelet openings 9, but for the purpose of illustrating this adjustment, these plates 8 have only been applied in the present instance to the upper band 1, the band 1 having headed pins 10 which are inserted in the larger end of the openings 9 and moved to position to the contracted neck portions thereof. From this it will be apparent that when it is desired to expand the bands, or in other words, to move the ends of the same away from each other, the pins 10 are moved from the outermost openings inward to the openings nearer the center of the plate 8 so that should the person wearing the support desire to loosen the effect of the same, the plates 8 will be adjusted upon the headed pins 10 so as to relieve the pressure of the resilient bands at the required point.

In Figs. 1 and 6, I have illustrated suitable bust supporting members to be used in connection with my improved abdominal support and they are herein illustrated as formed of a single supporting arm 11, the lower end of which is provided with suitable eyelet openings 12 adapted to receive the headed pins 13 formed upon the upper band 1 of the body of the support so that the arms 11 can be readily adjusted vertically. These arms 11 are to be formed of a light resilient material such as spring steel or whale-bone and are provided at their upper ends with suitable bust supports 13' while their lower ends project into suitable pocket members 14 carried by the body portion of the support so as to prevent the lower ends of the arms 11 from contacting with the body of the wearer. The pocket members 14 may be constructed of any suitable weight material and are to be supported upon the interior of the body of the support or, in other words, arranged between the inner lining of the support and the outer covering, said outer covering being generally indicated by the numeral 15 in Fig. 2, so that these pockets are entirely out of sight and access thereto is gained through suitable openings provided for at the upper edge of the supporter.

Particular attention is called to the adjustable plate 8 which is attached to a substantially C-shaped spring and provided to contract and expand said spring and to move the ends of the spring toward or away from each other and while I have illustrated this particular type of spring as used in connection with a support of the type described

heretofore, I wish it to be understood that this particular type of spring can be used for various other purposes.

From the above description taken in connection with the accompanying drawings, it will be readily apparent that I have provided an abdominal supporter which is simple in its construction, can be manufactured at comparatively low cost and wherein the same can be quickly and readily adjusted to accommodate figures of various sizes, can be worn with comfort and provide a neat outer appearance. It will also be apparent that I have provided in connection with a support of this character, a bust support which can either be worn with the abdominal support or entirely eliminated.

I claim:

1. An abdominal support comprising a band of resilient but non-extensible material consisting of a plurality of parts adjustably connected in such manner as to allow the band to be flexed.

2. An abdominal support comprising a band of resilient but non-extensible material consisting of a plurality of parts adjustably connected in such manner as to allow the band to be flexed and having its free ends overlapping.

3. An abdominal support comprising a plurality of resilient bands including spaced bands and a diagonal intermediate band connected at its intermediate portion to one of the spaced bands and having its ends connected to the ends of the other band.

4. In an abdominal support a C-shaped member and an adjusting plate detachably connected to the curved portions of said member whereby to contract and expand the member to move the ends of the same toward or away from each other.

5. An abdominal support comprising a plurality of resilient bands including an upper and lower band and a diagonal intermediate band connected to each of the upper and lower bands, one of the ends of said upper band being bifurcated and the other end of said band being movable within said bifurcation.

6. An abdominal support comprising a band of resilient but non-extensible material consisting of a plurality of resilient parts adjustably connected in such a manner as to allow the band to be flexed and means detachably connected with parts of the band whereby to expand or contract the same.

7. A corset comprising a plurality of resilient bands including upper and lower bands and a diagonal intermediate band connected to each of the upper and lower bands, a vertically adjustable supporting member mounted for adjustment upon the uppermost band and breast supports arranged at the upper ends of said vertically adjusting supporting members.

8. A corset comprising a plurality of spaced circularly bent resilient bands, a diagonal intermediate band connected to the upper and lower circular bands, pocket members carried by said bands, vertically adjustable supporting members mounted upon one of said bands having their lower ends extending into said pocket members and breast supporting members at the upper ends of said adjustable members.
9. An abdominal support including spaced bands of resilient but non-extensible material, a diagonal intermediate band connected at its intermediate portion to one of said spaced bands and having its ends connected to the other of the spaced bands and means detachably connected with one of said bands whereby to expand or contract the same.

In testimony whereof I affix my signature.
FOLKE FREDRICK NORDEN.
